UNITED STATES PATENT OFFICE.

FERDINAND G. GASCHE, OF CHICAGO, ILLINOIS.

EROSIVE-BLAST APPARATUS.

1,317,363.

Specification of Letters Patent. Patented Sept. 30, 1919.

Application filed October 20, 1917. Serial No. 197,592.

To all whom it may concern:

Be it known that I, FERDINAND G. GASCHE, a citizen of the United States, and a resident of Chicago, county of Cook, and State of Illinois, have invented certain new and useful Improvements in Erosive-Blast Apparatus, of which the following is a specification.

My invention relates generally to improvements in erosive blast apparatus, of which 10 the sand blast is an example, and relates more particularly to improvements in that part of the apparatus that governs and controls the direction, character, and motion of the blast and its impingement upon and 15 against the surfaces to be treated.

The general object of my invention is to increase the efficiency of erosive blast apparatus.

Further objects of my invention are to 20 simplify the construction of erosive blast apparatus; increase the durability thereof; and generally to improve the construction and operation thereof.

I propose to increase enormously the striking force of the abrasive material by utilizing 25 the potential energy of the air, steam, or other elastic medium commonly known as "pressure energy" through the use of expanding nozzles of proper size and shape.

The pressure energy still resident in a jet 30 of steam or other elastic medium at the time of leaving the throat or narrowest part of the nozzle can be applied to producing a greater velocity of the elastic medium than 35 that due to the pressure at the throat, provided the elastic medium is allowed to expand gradually in a conical or conical-like extension of the nozzle beyond the throat. The elastic medium may be thus confined 40 until it has attained an outlet pressure of the atmosphere, if desired, and the velocity at the exit of such a compound nozzle will be enormously increased over the exit 45 velocity of a nozzle without such an expansion. If such a compound nozzle is the outlet for air at 140 pounds absolute pressure, I find that the exit velocity will be far in excess of 1000 feet per second and may even reach 2400 per second. Furthermore, I

50 find that the frictional resistance in nozzles having such outlets can be made so low that practically all of this velocity energy of the jet is available for moving the particles of sand or other abrasive material. In other 55 words, that tendency to lateral expansion of the jet issuing from all other erosive blast

apparatus, with which I am familiar, is obviated by a device embodying my invention as above generally set forth. The jet also issues as nearly cylindrical with the consequent concentration of energy on a surface of impingement and a resident energy of the abrasive material of a magnitude not heretofore available in the arts.

In order to keep the wear of internal surfaces of pipes and fittings at a minimum, I cause the delivery of the abrasive material through a conduit separate from that carrying the working fluid up to the tip of a sand nozzle having an opening centrally and axially located with reference to the compound expanding nozzle. Furthermore, the tip of this sand nozzle is in the near vicinity of the throat of the expanding nozzle and causes the delivery of the particles of abrasive material in the central portion of the jet and near the region where a rapid change of velocity of the working fluid is imposed by the nozzle conditions. The parallelism of the stream lines of the fluid as passing through 80 the compound nozzle precludes the possibility of the impingement of the abrasive material on the walls of the nozzle and hence wear from this cause will be very little.

My invention consists generally in the 85 form, construction, arrangement, and coöperation of parts whereby the above named objects, together with others which will appear hereinafter, are attained and my invention will be more readily understood by reference to the accompanying drawing which 90 illustrates that embodiment of my invention which I consider the best at the present time.

The said drawing is a vertical central view showing part of the apparatus in section and 95 part thereof in elevation, in order to disclose more clearly the construction and coöperation of the parts.

While the device shown in the drawing is of a portable construction, my invention 100 fully contemplates a construction directing energies of such magnitude that a fixed or non-portable installation may be necessary. The apparatus comprises generally a body portion, 1, a handle portion, 2, and an exit, 105 outlet, or nozzle portion, 3. The nozzle 3 I shall refer to as a compound expansion nozzle, inasmuch as it comprises an outlet portion, 4, a smaller throat portion, 5, and a generally conical portion, 6, between the 110 portions 4 and 5 thus forming a conically diverging nozzle permitting the expansion

of the fluid and hence being an expansion nozzle. I prefer to make the increase in size from the portion, 5, to the portion, 4, about one unit for ten units of length where 5 air is the working fluid. 7 is an abruptly enlarged portion of the nozzle leading the air or steam under reservoir pressure to the orifice or throat 5, which is preferably provided with a rounded approach, 8, to minimize frictional losses. The nozzle chamber, 7, communicates immediately with the pressure chamber, 9, within the body, 1, of the apparatus. I prefer to make the nozzle part readily separable from the body to the end 15 that it may be quickly and easily removed for examination and repair, and to this end I provide it with screw threads, 10, for coaction with screw threads, 11, of the body. I also prefer to provide a nut-like portion, 12, on the nozzle for convenience in 20 removing and replacing. Leading from the chamber, 9, of the body portion is an air supply opening, 13, leading to the control valve, 14, and finally to the connection, 15, 25 designed for the attachment of a hose, pipe, or other conduit connected to a suitable pressure apparatus. The air valve, 14, operates in a suitable chamber provided with a properly surfaced interior by means of a 30 sleeve, 16, which is held in proper position by means of the opposed nuts, 17, and 18. The sleeve, 16, is provided with openings, 19, and 20 for coaction with the groove, 21, of the valve, 14, when the valve is aligned 35 therewith. I prefer to make the valve, 14, close automatically and to this end I provide a spring, 22, normally pressing it upward to the closed position indicated in the drawing. For the purpose of actuating the 40 valve, I provide a stem, 23, connected to a link, 24, which in turn is secured to the trigger, 25, pivoted to the handle, 2, at 26. Thus when the hand embraces the handle, 2, it is in a position convenient to actuate 45 the trigger, 25, by an upward pressure. The handle, 2, also contains a button, 27, reacting against a spring, 28, and through the medium of rod, 29, and pivoted lever, 30, serving to raise or lower the stem, 31, provided with the needle-valve end, 32. The 50 movement of the needle-valve obviously controls the rate of efflux of the sand or other abrasive material through the opening, 32', of the sand nozzle, 33. The sand or other 55 abrasive material is contained within the member, 33, and is admitted thereto through an opening 34, connected to any suitable source of supply, the sand being preferably delivered under pressure. I bring the sand 60 outlet, 32', into near proximity to the throat, 5, of the compound nozzle such as to favor a central delivery of a stream of abrasive material with reference to the currents of stream lines of elastic medium that are being 65 formed at 7. These streams of elastic fluid

attain a considerable velocity at the throat, 5, but reach their highest velocity at the outlet, 4, for the reasons heretofore described.

It will be noted that the elastic fluid practically surrounds the stream of abrasive material as it passes through the throat and hence an abrading action on the compound nozzle is prevented. By using a suitable length expanding nozzle, the pressure of the working fluid will be so reduced as it reaches 70 the outlet, 4, that the jet will issue in substantially cylindrical form and with but little tendency to lateral expansion for a distance of many inches. During all of the travel of the working fluid from the vicinity 75 of the throat, 5, to the above distance remote from the nozzle, there is a continued acceleration of the particles of abrasive material within the jet, and a tendency to attain the actual velocity of exit of the working 80 fluid. 85

While I have described a compound expanding nozzle with a conically divergent expansion chamber, the sections of said nozzle are not necessarily circular in order to 90 realize the advantages of my invention. If particular or special applications of the erosive blast apparatus requires square, rectangular or other sections of nozzle, the underlying principle of conversion of pressure 95 energy into velocity energy of the working fluid can, by providing a controlled expansion of the elastic fluid, be applied.

It may be desirable to make the nozzle 3 of different lengths for different work, 100. This may be accomplished practically by providing nozzle sections, one of which is shown by means of dotted lines in the drawings.

I claim:

1. In an erosive blast apparatus, a body portion formed with a pressure chamber for an elastic fluid; a compound nozzle having a throat portion, an abruptly enlarged chamber leading from the throat portion and communicating with the pressure chamber, and a relatively long conical conduit leading away from the throat and pressure chamber; and an abrasive material conduit terminating adjacent the throat of the compound nozzle and adapted to discharge material into the conical conduit, as and for the purpose specified.

2. In an erosive blast apparatus, a body portion formed with a pressure chamber for an elastic fluid; a compound nozzle having a throat portion, an abruptly enlarged chamber leading from the throat portion and communicating with the pressure chamber, and a relatively long conical conduit leading away from the throat and pressure chamber; and an abrasive material conduit terminating adjacent the throat of said compound nozzle and having an opening positioned to discharge material centrally and 130

axially into the conical conduit, as and for the purpose specified.

3. In an erosive blast apparatus, a body portion formed with a pressure chamber 5 for an elastic fluid, a compound nozzle having a throat portion, an abruptly enlarged chamber leading from the throat portion and communicating with the pressure chamber, and a relatively long conical conduit 10 leading away from the throat and pressure chamber; an abrasive material conduit terminating adjacent the throat of said compound nozzle and having an opening positioned to discharge material centrally and 15 axially into the conical conduit; and means for controlling the rate of efflux of material from said material conduit.

4. In an erosive blast apparatus, a body

portion formed with a pressure chamber for an elastic fluid; a compound nozzle having a 20 throat portion, an abruptly enlarged chamber leading from the throat portion and communicating with the pressure chamber; a relatively long conical conduit leading away from the pressure chamber; and an 25 abrasive material conduit terminating adjacent the throat of the compound nozzle and formed and adapted to discharge abrasive material under pressure into the conical conduit, so that upon its issuance from 30 the abrasive material conduit it shall already have gained a certain initial velocity.

In testimony whereof, I have hereunto set my hand this 10th day of October, 1917.

FERDINAND G. GASCHE.
